REVERSIBLE BOBBIN RECEIVING BAG

Walter H. Wakefield, Worcester, Mass., assignor
to Crompton & Knowles Loom Works, Worcester,
Mass., a corporation of Massachusetts

Application December 22, 1945, Serial No. 636,951

14 Claims. (Cl. 139—255)

1

This invention relates to improvements in bobbin receivers for weft replenishing looms and it is the general object of the invention to provide a receiver which is reversible or can be turned inside out to discharge bobbins therefrom.

In weft replenishing operations the spent or exhausted bobbins are discharged downwardly from the shuttle and are ordinarily collected in a can or the like which must be lifted and inverted when the bobbins are to be discharged therefrom. It is an important object of the present invention to provide a bobbin receiver including a flexible bag mounted on the loom and provided with pull cords or the like by which it can be turned inside out to effect forward discharge of the bobbins. The cords are preferably attached to the bottom of the bag and then pass through guides at the rear part of the bag. With such an arrangement upward pulling of the cords will swing the rear part of the bag forwardly away from operating mechanism, such as the picker stick, and as the bottom passes through the mouth of the receiver the bag will be reversed.

It is another object of the invention to provide the bobbin receiver with a rigid top frame pivotally mounted at the rear part thereof to the loom so that the frame can be turned from the normal rearwardly inclined position thereof to a discharge position in which the mouth of the receiver will face forwardly so that when the bag is turned inside out the bobbins will be discharged in a frontward direction.

Weft replenishing looms ordinarily include a bobbin guiding chute which reciprocates backwardly and forwardly in a given path and down which the discharged bobbins move toward the receiver. The mouth of the receiver ordinarily extends under the forward part of this path. When the upper part of the receiver is pivoted as already stated it can swing down to its discharge position without interfering with the path of the chute.

With these and other objects in view which will appear as the description proceeds, my invention resides in the combination and arrangement of parts hereinafter described and set forth.

In the accompanying drawing, wherein a convenient embodiment of my invention is set forth,

Fig. 1 is a side elevation of part of a loom showing the invention in normal position, parts of the loom being in section.

Fig. 2 is a plan view of the receiver looking in the direction of arrow 2, Fig. 1.

Fig. 3 is a vertical section on line 3—3 of Fig. 2,

Fig. 4 is an enlarged detailed plan looking in

2

the direction of arrow 4, Fig. 1, and showing the parts in normal position.

Fig. 5 is a view similar to Fig. 4 but showing the parts in discharge position.

Fig. 6 is a view similar to a part of Fig. 1, but showing the receiver in discharging position preparatory to emptying the bobbins therefrom.

Figs. 7 and 8 are diagrammatic views showing successive steps in turning the bag inside out for the purpose of discharging the bobbins therefrom, and

Fig. 9 is a front elevation looking in the direction of arrow 9, Fig. 4.

Referring particularly to Figs. 1, 2 and 3, the 15 loom frame 10 supports a lay 11 provided with a shuttle box 12 to receive a shuttle S. A bobbin guiding chute 13 is secured to the lay and extends downwardly and forwardly from a position under the shuttle box to guide spent or exhausted 20 bobbins which are discharged downwardly from the shuttle S during replenishing operations. The lay moves backwardly and forwardly during loom operation so that the chute 13 traverses a back and forth path. Replenishing operations 25 occur when the chute is at the left end of its path as viewed in Fig. 1, or at so-called front center.

The bobbin receiver forming the subject matter of the present invention is indicated generally at R and includes an upper frame F, a bag B 30 made of cloth or similar flexible material, and a support A mounted on the loom frame. The frame F may be made of a single bar or rod bent as indicated in the drawing and will have a rear member 15 more or less parallel to the lay extending outwardly from the loomside and then bent forwardly to form the outer side member 16, after which the bar is bent back toward the loom frame to provide a front member 17 which in turn is bent rearwardly to form an inner side member 18. The members 15—18 form an open 40 preferably rectangular mouth M which normally faces upwardly and receives bobbins descending from the chute 13.

The inner side member 18 at the rear part 45 thereof is bent downwardly to form a stop arm 20 and then horizontally toward the loom frame to provide a journal 21. The journal extends into and is rotatable and slidably in a bearing hub 22 on the support A, the latter being fastened to the loom frame as at 23. The axis of the hub is horizontal and preferably parallel to the lay.

The hub 22 has extending laterally from the forward part thereof a stop lug 25 provided with 50 a rearwardly facing vertical groove 26 propor-

tioned to receive the stop arm 20. A second lug 27 projects from bearing 22 beyond and below lug 25 and spaced from the latter to form a notch 28. The notch receives stop arm 20 and lug 27 supports it when bobbins are being discharged from the receiver. The journal 21 extends beyond the inner end of bearing hub 22 and has secured thereto a collar 30 which will be spaced from the bearing 22 when the stop arm 20 is in the notch or recess 26. The collar 30 is so located that the journal 21 can slide along the bearing 22 in a direction away from the loom-side sufficiently to enable the stop arm or member 20 to clear the upper part of the lug 25 but not far enough to move beyond the lower stop lug 27.

The bag B may be made of any sufficiently flexible and wear resisting material and has its upper edges attached in any approved manner to the members 15-18 of the frame F. The interior of the bag will have secured thereto two sets of guide means such as eyelets, one of these sets being preferably adjacent to that part of the bag which depends from the inner side member 18 and the other set being on the opposite side of the bag which depends from the member 16. Each set of guides will have a forward eyelet 35, a lower rear eyelet 36, and an upper rear eyelet 37. A lifting cord or strap 38 is provided for each set of eyelets, and each cord is fastened to its corresponding forward eyelet 35 and then is trained through its eyelets 36 and 37 and extends upwardly to the forward part of the mouth of the bag and may have a hook 40 thereon to be held by the front member 17 of the frame F. I find it is preferable to have the upper rear eyelets 37 a considerable distance below the back member 15, this distance being preferably greater than the distance between the front and back members 17 and 15, respectively.

Under normal conditions the parts will be as shown in Fig. 1, the stop arm 20 being held in notch 26 by the weight of the receiver which is in front of its pivot. The collar 30 will be spaced inwardly or toward the loom frame from the bearing 22 and the mouth M will be facing upwardly but will be inclined downwardly and rearwardly with the front member 17 above or at a higher level than the rear member 15 of the frame F. The reason for this relation is to prevent accidental forward escape of bobbins descending from the chute 13 if they should happen to rebound from other bobbins already in the receiver. The cords or straps 38 will be slack and of sufficient length to allow the bag to hang freely so that its full capacity will be available for the collection of bobbins.

When it is desired to empty the receiver of the bobbins contained therein frame F will be rocked a slight distance in a clockwise direction as viewed in Fig. 1 to disengage the stop arm 20 from the notch 26, after which the receiver will be moved from the position of Fig. 1 away from the loom frame a slight distance as the journal slides in the bearing until the parts assume the position shown in Fig. 5. The stop arm 20 will now be beyond lug 25 and over lug 27 and frame F will be dropped and will pivot in a counter-clockwise direction as viewed in Fig. 1 around its pivotal support A. The stop arm 20 will now be on lug 27, and a slight inward movement toward the loom will cause arm 20 to enter notch 28. This operation will place the receiver as shown in Fig. 6 with the mouth M inclined downwardly and forwardly and opening in a direction

away from the lay. The cords 38 are now pulled upwardly through the mouth the effect of which is to lift the back part of the bag and crowd the bobbins forwardly, after which continued pulling on the cords will eventually turn the bag inside out. During this operation the bag passes through the successive positions shown in Figs. 6, 7 and 8. When in the position in Fig. 8 the bobbins will fall into a receiver 45 which is moved from loom to loom by the attendant.

After the bag is emptied the attendant returns it to its normal position, pushing the bag back through the frame F and slackening the cords 38. The frame F is then moved outwardly to disengage stop arm 20 from notch 28 and is then raised by an angular movement which is clockwise as viewed in Fig. 1, until the stop arm 20 is slightly behind the stop lug 25, after which the receiver is moved a short distance toward the loom frame so that the stop arm 20 can enter notch 26. The receiver is now reset and will remain in a stable position due to its weight as already described.

When the bag is being turned inside out the upward pull on cords 38 may tend to raise frame F. This motion will be prevented by engagement of stop arm 20 with the underside of lug 25. It may not be necessary in all instances to use the notch 28, since the attendant can hold frame F down with one hand while pulling on cords 38 with the other hand.

The hooks 40 shown for the upper ends of the cords 38 are not essential, since the cords can fall into the bag and the attendant can lift them from under the accumulated bobbins preparatory to emptying the bag. While I have shown one means for holding the receiver in its normal position with the front member 17 above the rear member 15, yet I do not wish to be limited to the particular means shown for instance in Figs. 4 and 5 for accomplishing this result.

From the foregoing it will be seen that I have provided simple means by which a cloth bobbin receiver can be turned inside out in order to discharge bobbins from it. It will also be seen that the frame F is so mounted that it can be swung from a normal downwardly and rearwardly inclined position to a discharge position in which it is inclined downwardly and forwardly. It will further be seen that the cords or straps 38 afford means for lifting the bottom of the bag to permit reversal of it so that it can be drawn through the mouth M of the frame F, and in this connection it will also be noted that the eyelets 35 through which the cords extend are located on the rear parts of the bag so that these parts will be moved forwardly away from operating mechanism of the loom as the bottom of the bag is raised. The pivot for the frame is at the rear part thereof and the mouth of the receiver moves to discharge position without interfering with the back and forth motion of the bobbin chute.

Having thus described my invention it will be seen that changes and modifications may be made therein by those skilled in the art without departing from the spirit and scope of the invention and I do not wish to be limited to the details herein disclosed, but what I claim is:

1. In a bobbin receiver for a weft replenishing loom, a frame at the upper part of the receiver defining a mouth therefor, a flexible bag suspended from said frame, and means connected to the bag for turning the latter inside out to effect discharge of bobbins from the bag through the mouth.

2. In a bobbin receiver for a weft replenishing loom, a frame at the upper part of the receiver defining a mouth therefor, a flexible bag suspended from said frame, and means attached to the lower part of the bag to lift the bottom of the bag toward said frame to discharge bobbins in said bag through said mouth.

3. In a bobbin receiver for a weft replenishing loom, a frame at the upper part of the receiver defining a mouth therefor, a flexible bag suspended from said frame, and means connected to the interior of the bag and positioned to be drawn upwardly through said mouth for the purpose of turning the bag inside out to discharge bobbins in the bag through said mouth.

4. In a bobbin receiver for a weft replenishing loom, an open frame at the top of the receiver defining a mouth therefor, means to support the frame with the front part of the mouth at a level below the back part of the mouth, a flexible bobbin holding bag suspended from said frame, and means connected to the interior of the bag and effective when raised to lift the bottom of the bag and turn the latter inside out.

5. In a bobbin receiver for a weft replenishing loom, an open frame, means to support said frame with the front part thereof at a level lower than the back part thereof, a flexible bobbin holding bag suspended from the frame, and means connected to the interior of the bag which when pulled upwardly through the frame turns the bag inside out to effect discharge of bobbins in the bag through the frame.

6. In a bobbin receiver for a weft replenishing loom, an open frame, means to support said frame with the front part thereof at a level lower than the back part thereof, a flexible bobbin holding bag suspended from the frame, and means attached to the lower part of the bag to lift the bottom of the bag toward said frame to discharge bobbins in the bag through said frame.

7. In a bobbin receiver for a weft replenishing loom, an open frame for the upper part of the receiver defining a mouth therefor, a flexible bag suspended from said frame, and flexible lifting means within the bag connected to the lower part thereof and extending along the rear part of the bag and effective when raised to lift the bottom of the bag and turn the latter inside out to discharge bobbins in the bag through the mouth.

8. In a bobbin receiver for a weft replenishing loom, an open frame, means to support said frame with the front part thereof at a level lower than the back part thereof, a flexible bobbin holding bag suspended from the frame, flexible means connected to the bag adjacent to the bottom thereof and extending along the rear part of the bag and then upwardly through the mouth and effective when raised to lift the bottom of the bag and pull the rear part of the bag forwardly and turn the bag inside out to effect discharge of bobbins within the bag through the mouth.

9. In a bobbin receiver for a weft replenishing loom, an open frame, means to support said frame with the front part thereof at a level lower than the back part thereof, a flexible bobbin holding bag suspended from the frame, guide means arranged along the rear part of the bag, and flexible lifting means extending through said guide means and attached to the bottom of the bag, said flexible means when lifted moving the rear part of the bag forwardly and raising the bottom of the bag and effective to turn the bag inside out.

10. In a bobbin receiver for a weft replenishing loom, an open frame for the upper part of the receiver, a flexible bag suspended from the frame, means carried by the loom constituting a horizontal pivot the axis of which is near the rear part of the frame and around which the latter is movable downwardly from the normal position thereof, and releasable means holding said frame in normal position and inclined downwardly and rearwardly, said means when released permitting downward swinging of said frame to a position in which the latter is inclined downwardly and forwardly.

11. In a bobbin receiver for a weft replenishing loom, an open frame forming the upper part of the receiver, a flexible bag suspended from the frame, a pivotal support for the rear part of the frame mounted on the loom, and disengageable means normally holding said frame in a normally downwardly and rearwardly inclined position, said means when disengaged permitting said frame to swing downwardly around said pivotal support to a discharge position in which said frame is inclined downwardly and forwardly.

12. In a bobbin receiver for a weft replenishing loom, an open frame for the upper part of the receiver having a horizontally extending journal at the rear part thereof, a sliding and pivotal support for said journal mounted on the loom, and a stop for said frame, said journal when in normal longitudinal position with respect to said bearing causing said stop to engage said frame and support the latter in a downwardly and rearwardly inclined position, and said journal when moved longitudinally in a given direction in said bearing causing said frame to move away from said stop, whereupon the latter can fall to a discharge position in which it is inclined downwardly and forwardly.

13. In a bobbin receiver for a weft replenishing loom, an open frame defining a mouth for the receiver, a bag suspended from said frame, a horizontally extending journal on the rear of said frame, a bearing for said pivot on the loom, and support means for said frame with respect to which the frame is movable from engaging position to non-engaging position, said support means normally holding the frame with the mouth inclined downwardly and rearwardly, when the frame is in engaging position, and said frame when in non-engaging position being movable pivotally downwardly to a position in which the mouth is inclined downwardly and forwardly.

14. In a bobbin receiver for a weft replenishing loom having a bobbin chute reciprocating backwardly and forwardly in a given path, an open frame for the upper part of the receiver defining a mouth for the latter, a flexible bag suspended from said frame, a pivotal connection between the loom and the rear part of said frame, and support means for the frame, said support means and frame being movable with respect to each other to two different relative positions, said frame when in one of said positions being held by said support means with the mouth inclined downwardly and rearwardly and extending under said path, said frame when in the other of said positions being capable of downward movement around said pivotal connection to a position in which the mouth is inclined downwardly and forwardly and forward of said path.
